UNITED STATES PATENT OFFICE.

JOHN WALLACE LAURENT, OF SPOKANE, WASHINGTON, ASSIGNOR OF ONE-THIRD TO
WILLIAM KELLINGER, OF SPOKANE, WASHINGTON.

CURRENT-MOTOR.

1,114,489.

Specification of Letters Patent.

Patented Oct. 20, 1914.

Application filed July 22, 1913. Serial No. 780,456.

To all whom it may concern:

Be it known that I, JOHN W. LAURENT, a citizen of the United States, and a resident of Spokane, in the county of Spokane and 5 State of Washington, have invented a new and Improved Current-Motor, of which the following is a full, clear, and exact description.

My invention relates to a motor supported 10 on a floating structure and adapted to be raised and lowered relatively to the stream, the motor when lowered, presenting a broadside upstream.

The novel features of the invention will 15 be particularly explained in the specific description following.

Reference is to be had to the accompanying drawings forming a part of this specification, in which similar characters of reference 20 indicate corresponding parts in all the views.

Figure 1 is a side elevation of a motor and its supporting structure embodying my invention; Fig. 2 is a vertical section at 25 right angles to Fig. 1, the section being taken in front of the current wheel; Fig. 3 is a sectional plan view; Fig. 4 is a detail sectional view of one of the float elements and the clamp bars thereof; and Fig. 5 is 30 a detail of one of the bearings for the current wheel.

In constructing a practical embodiment of my invention in accordance with the illustrated example, longitudinal bars 10 are 35 arranged in pairs to clamp a series of barrels 11 at each side of the structure, as hereinafter explained, to give buoyancy to the latter, the pairs of longitudinal bars 10 being connected by outer transverse frame bars 12 and inner transverse frame bars 13. A vertical frame is erected on the float frame, and includes guide uprights 14 to 40 guide the vertically sliding motor frame 15 carrying a current motor 16. The frame 45 15 may comprise side members 17, a top cross bar 18, a bottom cross bar 19, and an intermediate cross bar 19^a. On the side members 17 of the sliding frame guide plates 20 are secured and project laterally to have 50 guiding engagement with the uprights 14. The lower end 14^a of the guide upright 14 at the down-stream side of the structure is 55 hinged, being provided with a block 21 having a hinge connection 22 with the adjacent longitudinal bar 13, the hinge leaves

23 being secured respectively to the block 21 and bar 13, as seen in Fig. 1. A diagonal brace arm 24 extends from near the lower end of the hinged guide part 14^a, and its outer free end, when the part 14^a is in the lowered position and in line with the upper portion of the upright 14, may be sprung into engagement with the adjacent outer longitudinal bar 12, whereby the hinged lower end 14^a is braced against the pressure 60 exerted on the current wheel 16. When the motor 16 is raised to inoperative position, the end 14^a of the guide frame may be swung upwardly on its hinge out of the stream so that it will not engage floating 65 logs or the like and be damaged. The transverse bars 12 are secured to uprights 25 that rise from the longitudinal bars 10 of the float frame, and said transverse bars may be braced by diagonal braces 26, 27, extending to the 70 uprights 14; the latter may also have diagonal braces 14^c disposed in a plane normal to the braces 26, 27. In the lowered position of the motor frame 15, the ends of the top cross bar 18 thereof rest on stops 28 75 on the uprights 14. Said uprights may be provided with friction rollers 29, for rolling contact with the vertical sides 17.

To raise and lower the motor frame a tackle is provided, consisting of a rope 30 80 bent around a sheave 31 of the cross bar 18, and over sheaves 32, 32^a on the top bar 14^b of the fixed frame, and downward to a winding drum 33 having a crank handle 34, said drum being suitably mounted in a laterally 85 projecting frame 35 above the floats 11.

The shaft 36 of the current wheel 16 turns in bearings 37 on the vertical side members 17 of the sliding frame, and the countershaft 38 above the current wheels turns in bearings 39 on said side members. The shafts 36, 38, have chain wheels 40 over which a sprocket chain 41 runs, for driving the shaft 38 from the current wheel. The shaft 38 has a pulley 42 from which power is taken 90 by a rope or belt (not shown), to any suitable machinery on shore. The end thrust of the shaft 36 of the current wheel is received by an angle bracket 43 (best shown in Fig. 5), the angular end 44 of which receives the 95 contact of the rounded end 36^a of the said shaft.

It is advantageous to employ barrels as the float elements, because their size and number can be adapted to the size of the structure 100 105 110

and current motor, and in order to securely clamp the barrels in a convenient manner, the longitudinal bars 10 are provided on their inner sides with preferably round blocks 10^a, which are received in the ends of the barrel, outside the heads 11^a thereof, whereby the tightening up of bolts 10^b which extend through the pairs of bars 10, will firmly clamp the barrels in position.

10 By the described construction a simple and strong structure is obtained, having provision for the convenient raising and lowering of the motor for the proper bracing of the frame parts and the motor.

15 Having thus described my invention, I claim as new, and desire to secure by Letters Patent:

1. In a current motor, a float frame, a vertical sliding frame having guided movement on the float frame, a current motor carried by the sliding frame, means for raising and lowering the sliding frame, the float frame having the lower portion of the guide member at the down stream side of the 25 motor hinged to be swung upward when the

current motor is raised, and adapted to be lowered when the motor is to be lowered.

2. In a current motor, a float frame having front and rear vertical guide members thereon, a vertically sliding motor frame having guided movement on said guide members, a current motor carried by the sliding frame, and means for raising and lowering said sliding frame, the rear vertical guide member on the float frame having its lower portion hinged to swing from a position in line with the upper portion of the said guide member to a raised position, and a brace carried by said hinged portion of the guide member, and adapted when in the lowered position to be pressed against a relatively fixed portion of the float frame.

In testimony whereof I have signed my name to this specification in the presence of two subscribing witnesses.

JOHN WALLACE LAURENT.
